CHRISTMAS ORNAMENT

Miller C. Johnson, Jr., 7595 Terri Drive,
Westland, Mich. 48185

Filed Feb. 13, 1969, Ser. No. 15,762

Term of patent 14 years

Int. Cl. D11—05

U.S. Cl. D29—1

FIG. 1 is a perspective view of my new design for a Christmas Ornament.

FIG. 2 is a schematic side elevation of my new design on a reduced scale, with some of the detail shown in FIG. 1 omitted for clarity.

FIG. 3 is an enlarged perspective view of a representative portion of one of the suspending cords shown in FIG. 1 showing a typical series of applied ornaments.

I claim:

The ornamental design for a Christmas ornament, as shown and described.
